(57) **CLAIM**

The ornamental design for a base cradle for a communications headset, as shown and described.

DESCRIPTION

FIG. 1 is a front-right perspective view of a base cradle for a communications headset showing my new design;
FIG. 2 is a back-top-left perspective view thereof;
FIG. 3 is a front view thereof;
FIG. 4 is a back view thereof;
FIG. 5 is a left side view thereof;
FIG. 6 is a right side view thereof;
FIG. 7 is a top view thereof; and,
FIG. 8 is a bottom view thereof.

In the drawings, the claimed design is defined by the shaded surfaces. The broken lines shown in dot-dot form depict unclaimed features and environment that form no part of the claimed design.

The remaining broken lines are shading or contour lines and are not actually visible on the surface.
